Arthur D. Altemiller, Afton, Mo., assignor to
Hercules Steel Products Corporation, Galion,
Ohio, a corporation of Delaware

Application July 8, 1953, Serial No. 25,840

Term of patent 14 years

(CL. D81—10)

To all whom it may concern:

Be it known that I, Arthur D. Altemiller, a citizen of the United States, residing in Afton, St. Louis County, State of Missouri, have invented a new, original, and ornamental Design for a Combination Hot Dog Steamer and Bun Warmer, of which the following is a specification, reference being had to the accompanying drawing forming a part thereof.

Fig. 1 is a perspective view showing the top, front and one side of a combination hot dog steamer and bun warmer embodying my new design;

Fig. 2 is a perspective view showing the top, rear and other side thereof; and

Fig. 3 is a side elevational view thereof on a reduced scale.

I claim:

The ornamental design for a combination hot dog steamer and bun warmer, substantially as shown.

ARTHUR D. ALTEMILLER.
